UNITED STATES PATENT OFFICE.

AMANDUS M. HEMBERG, OF MINNEAPOLIS, MINNESOTA.

HARVESTER.

SPECIFICATION forming part of Letters Patent No. 792,592, dated June 20, 1905.

Application filed November 17, 1904. Serial No. 233,113.

To all whom it may concern:

Be it known that I, AMANDUS M. HEMBERG, a citizen of the United States, residing at Minneapolis, in the county of Hennepin and State 5 of Minnesota, have invented certain new and useful Improvements in Harvesters; and I do hereby declare the following to be a full, clear, and exact description of the invention, such as will enable others skilled in the art to which it 10 appertains to make and use the same.

My invention relates to harvesters of a class which are adapted to be pushed by horses hitched thereto in the rear of the body of the harvester, and has for its object to improve 15 the same in the several particulars hereinafter noted.

The invention consists of the novel devices and combinations of devices hereinafter described, and defined in the claims.

20 In the accompanying drawings, which illustrate my invention, like characters indicate like parts throughout the several views.

Figure 1 is a plan view of the improved harvester. Fig. 2 is a vertical longitudinal section taken on the line $x^2 x^2$ of Fig. 1. Fig. 3 is a transverse vertical section taken on the line $x^3 x^3$ of Fig. 1, some parts being left in full. Fig. 4 is an enlarged sectional view showing certain of the parts shown in Fig. 3, 25 sectioned on the same line as in said Fig. 3. Fig. 5 is a detail in section on the line $x^5 x^5$ of Fig. 3. Fig. 6 is a transverse vertical section on the line $x^6 x^6$ of Fig. 1. Fig. 7 is a horizontal section on the line $x^7 x^7$ of Fig. 6. Fig. 8 is a detail in section on the line $x^8 x^8$ of Fig. 6. Fig. 9 is a section taken approximately on the line $x^9 x^9$ of Fig. 1, some parts being left in full and some being broken away. Fig. 10 is a detail in section on the 30 line $x^{10} x^{10}$ of Fig. 9, some parts being broken away. Fig. 11 is a detail view, in front elevation, showing the parts immediately at the left of the line-mark $x^{11} x^{11}$ on Fig. 9; and Fig. 12 is a bottom plan view of a portion of 35 the machine-platform, showing also portions of the platform raising and lowering device.

The machine illustrated is of the so-called "low-down" type, and nearly all the running parts of the machine are supported directly 40 or indirectly on a long transversely-extended

platform-frame 1, which at its ends has heavy guides 2, in which trunnion-equipped raising and lowering bars 3 are mounted to slide vertically. Wheels 4 are loosely journaled on the trunnions of said bars 3.

55

A long and heavy reach bar or pole 5 is rigidly secured at its forward end to the rear central portion of the platform-frame 1. To the rear end of the reach or push bar 5 is swiveled a depending steering-bracket 6, to 60 the lower portion of which is journaled a pair of traction-wheels 7. The steering-bracket 6 is provided with oppositely-projecting arms 8, which are connected by chains 9 to the opposite ends of a lever 10, which is rigidly secured at its central portion to a steering-rod 11, which rod is journaled in the reach or push bar 5 and in a bracket 12, secured thereon, and is provided at its upper end with a hand-wheel 13, which is within convenient 65 reach of the driver seated on a seat 14, supported from the rear portion of said push-bar 5. The traction-wheels 7 are preferably connected for common movements, and one thereof is provided with a large bevel-gear 15, 70 that meshes with a pinion 16, carried by a short vertical shaft 17, which is passed axially through the pivot of the steering-bracket 6 and is journaled in the hub portion thereof. At its upper end the shaft 17 carries a bevel-gear 75 18, that meshes with a bevel-pinion 19, carried by the rear end of a long shaft 20. The shaft 20 transmits motion from the traction-wheels 7 to the power-driven parts of the machine, and it overlies the reach or push 80 bar 5, is journaled in bearings 21 and 22 thereon, and is provided at its extreme forward end with a sprocket 23.

85

The draft-horses are adapted to be hitched to the swingtrees of a two-horse evener 24, 90 the beam of which evener is pivotally attached to the push-bar 5 in front of the traction-wheels 7, as best shown in Figs. 1 and 2.

As means for raising and lowering the platform-frame 1 on its supporting-wheels 4 a 95 long cable 25 is attached to beams 1^a of the platform 1, preferably as shown at 25^a in Fig. 12. This cable 25 is extended longitudinally of the platform 1 in opposite directions, is passed over guide-sheaves 26, mount- 100

ed on the ends of said platform, and over guide-sheaves 27 on the upper ends of the bars 3, (see Figs. 3 and 5,) and from thence the cables are brought to the central portion 5 of the platform and are passed over guide-sheaves 28 and 29, as shown in Fig. 12. The ends of the cable 25 are brought along the pole or push-bar 5 to the rear portion thereof and are attached to windlasses 30, mounted 10 on said pole and provided with the usual or any suitable means for locking the cable in any desired adjustment. As is evident, by winding up the cable on the right-hand side of the pole the right-hand side of the machine 15 will be raised, while by winding the cable on the windlass on the left-hand side of the pole the left-hand side of the machine will be raised. Hence by manipulation of the two windlasses the platform 1 will be raised and lowered at 20 will.

The sickle 31, which is of the usual construction and is mounted in the usual way on the finger-bar 32 of the machine, is connected by a pitman 33 to a crank-disk 34, which is carried by the forwardly-projecting end of a roller-shaft 35, which is mounted on the sides of the platform-frame and is provided at its rear end with a sprocket 36. For a purpose which will presently appear the crank-disk 30 34 is provided with bevel-gear teeth 34^a. The roller-shaft 35 carries a roller 35^a. At the left-hand end of the platform 1 is an idle roller 37, and approximately in horizontal plane therewith a short distance at the left 35 of the roller 35 is an idle guide-roller 38. An imperforate deck 39, which is secured to the sides of the platform-frame, extends horizontally from the upper portion of the roller 37 to a point above the roller 38 and then inclines 40 upward tangentially in line with the upper portion of the roller 35^a. An endless slat-and-belt conveyer 40 runs over the deck 39, over the rollers 37 and 35^a, and under the roller 38. On the front and rear frame-boards 1^b of the 45 platform 1 are inwardly-projecting guide-cleats 41, that overlie the upper portions of the edges of the conveyer 40 and hold the same down onto the deck 39, as shown in Fig. 3.

50 In Figs. 1, 3, 4, 7, and 8 parts of the binder are illustrated, and of the parts illustrated it is only desirable to note the knotter-shaft 42, which carries a discharge-arm 43, and the needle-shaft 44, which carries a needle 45, both of which shafts are suitably journaled in the side 1^b of the platform-frame. A connecting-rod 46 connects an arm 42^a of the shaft 42 to an arm 44^a of the shaft 44. The needle-shaft 44 has rigidly secured stub-arms 60 44^b, in which is loosely journaled a rock-shaft 47, which at its forward end has a vertically-projecting trip-arm 48 and at its rear end has a horizontally-projecting arm 49. The numeral 50 indicates a binder-deck which is rigidly secured to the right-hand portion

of the platform-frame and is slotted to pass the needle 45, trip-arm 48, and various other parts.

Journaled in the sides 1^b of the platform-frame is a crank-shaft 51, which, as shown, 70 has two cranks, to each of which is pivoted a packer 52 in the form of a straight bar. The upper ends of the packers 52 reciprocate freely in eyes formed in keepers 53, which are pivoted on the transverse rod 54, supported by the said sides 1^b of the platform-frame. 75

The knotter-shaft 42 at its extreme outer end carries a fixed half-clutch 55, and the crank-shaft 51 near its outer end is provided 80 with a half-clutch 56. On the knotter-shaft 42 inward of its half-clutch 55 is a sprocket 57, which is loose, is adapted to slide, and is provided with a half-clutch 58, that co-operates with the half-clutch 55. Loose on the 85 crank-shaft 51 outward of the half-clutch 56 is a sliding sprocket 59, which has a half-clutch 60, that co-operates with the half-clutch 56. The numeral 61 indicates a shipper-lever which is pivoted at 62 to the rear side of the 90 platform-frame 1 and at its upper end is formed with reverse projections 61^a, the ends of which are pronged and engage annular grooves 57^a and 59^a, respectively, in the hubs of the sprockets 57 and 59. At its pivoted 95 lower end the shipper-lever 61 is provided with an inwardly-projecting arm 63, that overlies the free end of the arm 49 of the rock-shaft 47. A spring 64, attached to the upper portion of the arm 61 and to the adjacent side 1^b 100 of the platform-frame, normally holds the half-clutch 60 of the sprocket 59 interlocked with the half-clutch 56 of the crank-shaft 51 and holds the half-clutch 58 of the sprocket 57 out of engagement with the half-clutch 55 105 of the knotter-shaft 42. A sprocket-chain 65 runs over the sprocket 23 of the driving-shaft 20, under the sprocket 36 of the roller-shaft 35, over the sprockets 59 and 57, and under an idle guide-sprocket 66 on the rear portion 110 of the platform-frame, as best shown in Fig. 6.

The reel 67 is loosely journaled in a pronged supporting-frame 68, which frame is rigidly secured to the forward end of a long adjusting-rod 69 and is provided with guide-rod projections 70. The guide-rod 69 works loosely through the upper portion of a guide 71, and the rods 70 work through bearing-guides 72, which guides are rigid on the rear portion of the platform-frame. The rod 69 extends 120 rearward and terminates in a handpiece 73, which is within easy reach of the driver on the seat 14. The rear portion of said rod 69 is notched or serrated at 74 and is adapted to be locked to a perforated lock-bracket 75 by 125 means of a pin or other form of latch 76. The teeth 74 permit the rod 69 to be locked in different longitudinal adjustments, and the perforations in the bracket 75 permit said rod to be locked in different vertical adjust- 130

ments. By this means the reel may be adjusted vertically and from front to rear of the machine.

As a means for driving the reel and for permitting its adjustments the mechanism best illustrated in Figs. 9 and 10 is preferably employed. The right-hand end of the reel-shaft is provided with a miter-gear 77, that meshes with a miter-gear 78, through which gear 78 10 a square driving-shaft 79 is mounted to slide. An elbow-bracket 80 is journaled or loosely hung on a hub of the reel-supporting frame 68 and forms a bearing for the hub of the gear 78. The lower end of the shaft 79 is connected by a knuckle-joint 81 to a stub-shaft 82, which is journaled in a suitable bearing 83 on the adjacent side plate 1^a of the platform-frame. The shaft 82 carries a bevel-pinion 84, that meshes with the bevel-gear 20 34^a, before described.

Operation: The manner in which the machine may be raised and lowered and in which the reel may be adjusted has already been clearly described. It has also been made 25 clear that all of the running parts of the machine are driven from the traction-wheels 7 through the long shaft 20, which overlies the reach or push pole 5. The endless slat-and-belt conveyer 40 is continuously driven 30 under the forward movement of the machine from the roller 35^a. The reel also is continuously driven under the forward movement of the machine. Normally the packers 52 will be driven, and the parts of the binder will re- 35 main stationary in the position indicated by full lines in Figs. 3 and 4 of the drawings. When, however, the bundle on the binder-deck 50 has accumulated to the desired full size, the packers 52 acting thereon will force 40 the same against the trip-arm 48 with sufficient force to raise the arm 49 and rock the shipper-lever 61 outward against the tension of the spring 64. This outward movement of the shipper-lever 61 moves the two sprockets 45 57 and 59 outward, thereby uncoupling the crank-shaft 51 from the sprocket 59 and coupling the knotter-shaft 42 with the sprocket 57. The binder being thrown into action will tie and discharge the bundle in the usual way. 50 The discharge of the bundle releases the pressure on the trip-arm 48 and permits the spring 64, acting on the shipper-lever 61, to throw the knotter-shaft out of action and to again start the crank-shaft 51 and packers 52 into action. 55 The machine described, while simple and of small cost, is thought to be efficient for the purposes had in view and to have many features of improvement over harvesters of standard construction. 60 It is thought by me that this machine will have very light draft and that there will be no side draft on the machine and that the machine may be very easily operated and controlled by the driver from the seat at the rear 65 end of the reach or push pole.

It will of course be understood that the machine described is capable of considerable modification within the scope of my invention as herein set forth and claimed.

What I claim, and desire to secure by Letters Patent of the United States, is as follows:

1. A harvester having its body supported by a pair of wheels and having a rearwardly-projecting push-pole supported by a driving-wheel, and connections from said driving-wheel to the running parts of the harvester, substantially as described. 75

2. In a harvester, the combination with a platform-frame, and a pair of wheels supporting the same, of a push-pole rigidly secured 80 to said platform-frame at its forward end, a driving-wheel supporting the rear end of said push-pole, connections from said driving-wheel to the running parts of the harvester for driving the same, and means for moving 85 said driving-wheel, to steer the machine, substantially as described.

3. In a harvester, the combination with a platform-frame, of a reel, a sickle and conveyer, mounted thereon, wheels supporting 90 said platform-frame, a push-pole rigidly secured at its forward end to said platform-frame, a driving-wheel supporting, and pivotally connected to, the rear end of said push-pole, means for moving the driving-wheel 95 pivotally, to steer the machine, and driving connections from said driving-wheel to said reel, sickle, and conveyer, substantially as described.

4. The combination with a platform-frame 100 and a pair of wheels adjustably supporting the same, of a reel, a sickle, an endless conveyer, and packers, mounted on said frame, a push-pole rigidly attached to said platform-frame at its forward end, a driving-wheel pivoted to 105 and supporting the rear end of said push-pole, a seat carried by the rear end of said push-pole, driving connections from said driving-wheel to said reel, sickle, conveyer and packers, and a reel-adjusting device, a 110 platform-adjusting device, and a steering device, all extending to within reach of a person on the said seat, substantially as described.

5. A harvester having a rearwardly-projecting push-pole and a combined steering 115 and driving wheel at the rear end of said push-pole, and having driving connections that remain operative under the steering movements of the said wheel substantially as described. 120

6. The combination with a harvester having a rearwardly-projecting push-pole, of a combined steering and driving wheel supporting the rear end of said pole, and having driving connections that remain operative 125 under the steering movements of the said wheel a seat supported by the rear end of said pole, and a reel having an adjusting-rod extending to the rear end of said pole, substantially as described. 130

7. In a harvester, the combination with a platform-frame, and a pair of wheels adjustably supporting the same, of a push-pole rigidly secured to said platform-frame at its 5 forward end, a combined steering and driving wheel supporting the rear end of said pole, and having driving connections that remain operative under the steering movements of the said wheel a seat on the rear end of said 10 pole, and a platform raising and lowering de-

vice extending to the rear end of said pole, within reach from said seat, substantially as described.

In testimony whereof I affix my signature in presence of two witnesses.

A MANDUS M. HEMBERG.

Witnesses:

ROBERT C. MABEY,
